19 Claims. (Cl. 105—215)

The present invention relates to a new method and means for propelling railway motor wagons, small locomotives and like vehicles, driven by internal combustion engines, steam or electric motors.

It is customary to propel rail vehicles by driving one of the axles of the vehicle through a suitable transmission either by chain gearing or Cardan shafts and bevel gearing. When the available motive power is small considerable difficulty is experienced in designing the transmission for existing axles of a railway vehicle on account of the necessarily heavy sections of such axles which have to support heavy loads and resist shocks and torsion. Also on account of the heavy nature of standard railway wagons, when attempting to use small engines, it is difficult to design the transmission strong enough to withstand the heavy stresses which occur at starting, especially when using ordinary change gear mechanisms and clutches, for the reason that the stresses depend on the skill of the driver in changing gear and manipulating the clutch. Consequently heavy and expensive gearing is necessary.

The present invention renders it possible to employ ordinary automobile engines and transmissions which are relatively of light construction, and adapting standard motor car components to propel relatively heavy railway stock and thus obtain very considerable reduction of cost and at the same time eliminate the risk of damaging the machinery by involuntary overloading at starting.

In a railway vehicle constructed in accordance with the present invention there is provided, in addition to the usual flanged metal wheels, an auxiliary axle suspended from the vehicle and having wheels provided with tires having a high coefficient of friction, which wheels constitute driving wheels and means for adjusting the loading on said auxiliary axle whereby the wheels on said auxiliary axle are normally pressed into contact with the rails to such a degree as will enable them to drive the vehicle to suit varying conditions, the flanged metal wheels retaining their guiding and supporting function.

Preferably the auxiliary axle is formed of a rear axle of the automobile type suspended by an underframe articulated at one point to the vehicle. Preferably the auxiliary axle is of the automobile type, whilst transmission of the automobile type is also preferably employed, but any other form of transmission may be employed.

It has heretofore been proposed in a bogie for

a rail vehicle to provide an auxiliary axle having wheels furnished with pneumatic tires, the said axle functioning as a driving axle and also exercising a braking effort.

Various forms of the invention are illustrated diagrammatically by way of example in the accompanying drawings in which Figures 1, 2 and 3 show one form, Figure 1 being a transverse section, Figure 2 a longitudinal section and Figure 3 a plan. Figure 3a shows an arrangement similar to that shown in Figures 1-3 but in which the auxiliary axle is floating. Figures 4 and 5 are views similar to Figure 2 of modifications; Figure 6 is a longitudinal section of the arrangement shown in Figure 2 and showing the driving unit and Figures 7 and 8 show means for adjusting the loading on the auxiliary axle, Figure 8 showing a vehicle with a pair of auxiliary axles. Figures 9, 10, 11 and 12 show the method by which the wheels on the auxiliary axle can be brought into engagement with the flanged metal wheels. Figures 13, 14 and 15 show modified forms of the arrangement shown in Figures 7 and 8. Figures 16, 17, 18 show respectively in longitudinal section, transverse section and plan, another method of adjusting the loading on the auxiliary axle. Figures 19, 19A, 19B and 20 show other methods of adjusting the loading on the auxiliary axle. Figures 21, 22 and 23 show further modifications of the arrangement shown in Figures 7 and 8. Figures 24 and 25 show two forms of tires employed on the wheels carried by the auxiliary axle whilst Figure 26 shows in side elevation a complete vehicle according to the invention.

Referring now to the arrangement shown in Figures 1, 2 and 3, which arrangement is adapted to a railway wagon or vehicle, 1 is the usual vehicle frame supported by flanged metal wheels 2 on an axle 2' and springs 3. Suspended from the frame 1 is a frame 4 of the automobile type which frame 4 is in turn supported by wheels 5 carried on an auxiliary axle 6, the usual springs 7 being interposed between the axle 6 and frame 4. The wheels 5 constitute the driving wheels of the vehicle and are provided with rubber tires (such as are shown in Figures 24 and 25) the width of the tire being sufficient to ensure contact with the rail 8 all the time even when the vehicle passes round curves. The frame 4 is pivoted at 9 to the frame 1, which frame 1 is provided with depending arms 10 having holes 11 which can be brought into register with corresponding holes in the frame 4 so that, by means of a bar 12, the pressure on the auxiliary axle can be varied. Furthermore, the depending arms 10 are provided with holes 13

whereby the arms 10 constitute an adjustable axle mount by means of which the auxiliary axle 6 can be shifted transversely to the rails 8 to enable different portions of the tread of the tires to be moved into contact with the rails so that when one portion of the tread is worn out, a fresh one can be brought into use. 14 represents a universal joint, such as is generally employed in the transmission 15 of the automobile type.

10 Figure 3a shows an arrangement in which the frame 4 carrying the auxiliary axle is allowed to float between the depending arms 10 on the frame 1. In this arrangement a double acting piston 84, fast on a rod 85 slidably mounted between the 15 arms 10 for adjustment purposes according to varying loads, is located within a closed cylinder 86 to which the frame 4 is secured, the cylinder 86 being slidably mounted on the rod 85. 87 are springs which tend to keep the cylinder and frame centrally positioned between the arms 10. The piston 84 and cylinder 86 act as a dashpot and are so arranged as to damp the lateral oscillations of the frame, so that the system during the motion of the vehicle can oscillate from one side to the other a limited amount which can be controlled by the construction of the damping cylinder. In one way of effecting this more clearance is allowed between the piston and cylinder in its mean position thereby allowing free oscillations 30 to take place whilst the vehicle runs in a straight line; little clearance however is allowed towards the ends of the cylinder thereby damping out any oscillations when the vehicle is running in a curve.

35 In Figure 4 the spring 3 is connected in the usual manner at one end through a link 16 to the frame 1 and at the other end is connected to a link 17 centrally suspended from the frame 1 and adjustably connected by means of holes 18 to a link 19 which is connected to the auxiliary frame 4. In this arrangement the link 17 is secured to the link 19 at one particular hole 18 according to the load on the vehicle. The frame 4 is prevented from lateral movement by means of 40 guides 1'.

45 In order that the load on the auxiliary axle 6 will never exceed a predetermined amount which is substantially independent of the load on the vehicle, the arrangement shown in Figure 5 may be employed.

50 In this figure the auxiliary frame 4, is, as before, pivotally connected at 9 to the vehicle frame 1 whilst the other end of the frame 4 is connected to a piston 20 working in a cylinder 21 to which fluid under pressure from any convenient source is supplied through a pipe 22. In the arrangement shown in Figure 6, 23 represents an internal combustion engine which may be supported on the vehicle frame 1 in any convenient manner. The drive from the engine 23 is taken via a universal joint 14, and the transmission 15 to the auxiliary axle 6, either through a Cardan shaft and differential gear or from a differential gear mounted on the vehicle and connected by two chains to the wheels 5 in the ordinary manner, as employed on road vehicles.

55 In the arrangement shown in Figure 7 the auxiliary axle 6, differential gear, transmission and engine 23 form a single unit which is pivotally suspended at 24 from the frame 1 adjacent the engine. The rear end of the single unit is connected to a piston 20 in the same manner as is described in Figure 5 with reference to the auxiliary frame 4.

60 The pressure on the rubber tires in contact

with the rail can be very moderate as long as the rails are dry because the coefficient of friction between the rubber and the dry rails, is considerable. On account of such low loading on the auxiliary axle, if by any chance the transmission is overloaded, the only result will be that the wheels will slip. However when the rails are wet, the pressure can be automatically increased to the necessary degree. 5

65 The pressure on the tires should, therefore, be adjusted so that slip occurs at a predetermined maximum torque which the transmission can convey with safety according to the state of the rails.

70 In the arrangement shown in Figure 8 the vehicle is provided with a plurality of auxiliary axles 6, 6' so as to obtain higher tractive effort. As shown the drive from the engine 23 is transmitted in the usual manner to a differential gearing 25 to drive the first set of auxiliary wheels on the auxiliary axle 6 the drive being transmitted to a second differential 26 through universal joints 27 to drive a second set of auxiliary wheels. The auxiliary frame 4 is connected to a piston 20 as described in Figures 5 and 7 so that the load 25 on the auxiliary axles 6, 6' can be adjusted. If desired more than one engine such as 23 may be employed.

75 The invention renders it possible to adapt to any standard railway wagon any standard automobile driving axle, thereby combining the advantages of the light construction of ordinary automobile construction, while still employing a railway wagon of standard robust construction of axles and steel tires. The adaptation is simple 35 and inexpensive. In case of damage to the rubber tires through wear or accident, no harm occurs to the wagon as the ordinary axles which support the wagon are not affected in any way.

80 It may be pointed out that since the main axles 40 which support the wagon are steel tired and flanged, while the wheels of the auxiliary axles are light and rubber-tired but not flanged, the wear of these rubber tires is very considerably less than if they were themselves flanged. The 45 auxiliary axle and wheels can float a certain amount transversely to the rail and thus, instead of continually bearing on the same tread, the whole of the floating surface of the rubber tire will be utilized, such a floating arrangement being 50 shown in Figure 3A.

85 The load on the auxiliary driving axle can be reduced up to about one tenth of the weight of the wagon. Thus, a ten ton wagon can be propelled through an auxiliary axle loaded to only one ton. This very low loading will secure to the rubber tires a long life and the auxiliary axle can be of light construction. For climbing heavy gradients, the load may be adjusted, say, to two tons, which even in this case represents only one 60 fifth of the weight of the wagon.

90 In order that the vehicle may be driven in the reverse direction without the use of special reversing gears the auxiliary frame 4 is suspended in such manner that when it is desired to run forward the wheels on the auxiliary axle 6 are pressed into contact with the rails 8, as has been described with reference to Figures 1-8 inclusive, and when it is desired to run the vehicle in the reverse direction the axle is raised from its normal position so that the tires of the wheels on the said axle 6 are raised out of contact with the rails and are pressed against the flanged metal wheels 2. As shown in Figures 9 and 10 the auxiliary axle 6 is located near to one of the ordinary 75

axles 2' so that when the vehicle is running forward, as indicated by the arrow A in Figure 9, the steel tires on the ordinary wheels and the rubber tires of the wheels on the auxiliary axle 6 are close to one another but out of contact. In order to run the vehicle in the reverse direction, as shown by the arrow B in Figure 10, the auxiliary wheel 5 is raised out of contact with the rail 8 and into contact with the flanged metal wheel 2. In order to effect this motion one end of the auxiliary frame 4 is connected to a piston 28 working in a cylinder 29 which is pivoted at 30 to a bracket 31 on the vehicle frame 1. The auxiliary frame 4 is also pivotally connected to the axle box 32 carrying the axle 2' by means of a link 33 and to the frame 1 by a link 33'. The cylinder 29 is adapted to receive fluid under pressure from any convenient source through a port 34 so that pressure on the auxiliary axle 6 may be increased, as shown in Figure 9. The cylinder is also provided with a second port 35 whereby pressure can be supplied to the underside of the piston 28 instead of being supplied through the port 34. If pressure be supplied through the port 35 the piston 28 is raised, thereby lifting the auxiliary wheel 5 into contact with the flanged metal wheel 2, thereby driving the vehicle in the reverse direction.

The actuation of the link 33 to raise the auxiliary axle 6 may be effected as has been shown in Figures 9 and 10 or by mechanical or electrical means.

Figure 11 shows a modified form of the arrangement shown in Figures 9 and 10. The auxiliary frame 4 is connected to a bell crank lever 36, one arm of which is connected to the axle box 32, the other arm being connected to a double acting piston 28.

As shown in Figure 12 a plurality of auxiliary axles 6 may be provided each arranged as described with reference to Figures 9 and 10 or Figure 11 and as shown in this figure. Two pairs of auxiliary wheels 37 remain in contact with the rails 8 whilst the vehicle is proceeding in the direction of the arrow C whilst two other pairs 38 are in contact with the flanged wheels 2, all the auxiliary or non-flanged wheels being driven according to any of the methods previously described. To reverse the direction of motion of the vehicle the wheels 38 are lowered into contact with the rails 8 and the wheels 37 are raised into contact with the wheels 2, as has been described heretofore. In this way, irrespective of the direction in which the vehicle is running, the load due to the weight of the auxiliary axles is borne partially by the rails and partially by the vehicle. It will be noticed that the rotation of the auxiliary axles 38 and 37 are in opposite directions so that the vehicle will proceed in either direction.

In order that the pressure on the tires of the wheels 5 on the rails, or on the wheels 2, may be kept fairly constant and/or so that it may be adjusted at will by the driver the arrangement shown in Figure 13 may be employed. As shown in this figure there is interposed between the piston 28 and the link 33, which is pivoted to the auxiliary frame 4 and the axle box 32, a spring 40.

The necessary load on the auxiliary axle referred to above need not at any time be greater than just sufficient to ensure the grip of the driving tires on the rails. For example, the coefficient of friction of the rubber tires on the rails is high for dry rails and may be as great as 70 to 80% in favourable circumstances. In such circumstances therefore, a very moderate load on

the tires will ensure the necessary grip. On wet rails however, or when ice, sleet or snow covers the rails, the coefficient diminishes considerably and greater loads are necessary; such greater loading may however, be necessary only for a very limited time during the service of the vehicle. For example, supplementary loading may be necessary while the vehicle is travelling over a greasy patch of rails or during a sudden shower of rain or sleet, while during the remainder of the time and especially when coasting down hill a reduced load will be sufficient. As an illustration with a railway vehicle weighing 10 tons, and in which the auxiliary axle is provided with two rubber tires normal driving can be effected if the auxiliary axle has a load of $\frac{1}{2}$ ton per wheel, i. e. 10% of total load on driving axle. However, when climbing a gradient of say 1 in 40 in rainy weather it is necessary to increase the load on the rubber tires to as much as 2 to $2\frac{1}{2}$ tons on each wheel namely 4-5 tons on the driving axle i. e. 40-50% of total load.

If the load on the auxiliary axle is not adjustable within the limit of 1-5 tons it will be necessary to run all the time with the maximum of 5 tons on the driving axle. This will result in destruction of the rubber tires in very short time. Means are therefore provided for automatically adjusting the load on the auxiliary driving axles 6. The load on the driving axles 6 may be regulated through an adjustable loading and unloading device controlled or acted upon by the relative slip between the wheels 5 on the auxiliary axle 6 and the flanged metal wheels 2 supporting the vehicle.

One method of carrying this out is shown in Figure 14 in which the auxiliary axle 6 is carried on the auxiliary frame 4 through interposed springs 7 the auxiliary frame 4 being in turn articulated at one end to the frame 1 and at the other end supported from the frame 1 through an adjustable screw rack or like mechanical device (not shown) which acts upon one end of a bell crank lever 41, the other end of which is connected to a second bell crank lever 42 pivoted to the frame 4 and to a link 43 suspended from the frame 1. On actuation of the adjustable screw rack or like mechanical device the auxiliary frame 4 is lifted or lowered relatively to the frame 1 thereby enabling the loading of the auxiliary axle to be increased or decreased. The auxiliary frame 4 may be guided as shown in any of the preceding figures so as to prevent or limit movement thereof transversely to the rails. The screw rack or the like may be replaced by a pneumatic or hydraulic cylinder and piston or diaphragm as shown, for example, in Figure 5, to act between the auxiliary frame 4 and the frame 1 so that by varying the pressure of the air or other fluid in the cylinder the load on the auxiliary axle 6 can be varied accordingly. To vary the pressure on the auxiliary axle, an arrangement as shown in Figure 15 may be employed. The auxiliary axle 6 is connected through a suitable linkage such as a toggle 44 to the vehicle frame 1, the toggle being connected at its centre point to a piston 20 working in a cylinder 21 attached to the frame 1. By this means the relatively small increase in pressure of the fluid will give a relatively large increase of pressure on the auxiliary axle.

Referring now to Figures 16-18 inclusive, in order to actuate the adjustable screws, racks, pistons, diaphragms or the like loading devices by motion or pressure derived from the relative

slip between the wheels 5 of the auxiliary axle and the vehicle supporting wheels 2, the auxiliary frame 4 carries a differential 45 one member of which is driven by the auxiliary wheels 5 the other member being driven by the flanged wheels 2 both through chain mechanism 46. The third member of the differential carries a screw 47 working in a nut 48 carried by a member 49 pivoted to the frame 1 and connected by a link 50 to the frame 4. The arrangement is such that when no slip occurs the centre or driven member of the differential carrying the screw 47 remains stationary but when slip occurs this member rotates, causing the nut 48 to move vertically downwards, which movement causes the adjustable loading member 49 to actuate so as to increase pressure on the auxiliary axle 6 through the link 50. In order that the built-up pressure may slowly be released, when slip has ceased, the diameter of the chain wheel mechanism on the auxiliary axle 6 is made slightly larger, so that the nut 48 tends slowly to unwind.

Another method of automatically increasing the load on either the driving wheels 5 or the supporting wheels 2 when slip occurs is shown in Figures 19 and 20. This arrangement consists in replacing the screw and nut mechanism and link mechanism 49 and 50 by a compressor pump or the like which will create the fluid pressure for operating the pneumatic or hydraulic devices referred to previously. In Figure 19, the auxiliary wheels 5 drive, for example through a chain mechanism 46, although any other means of drive may be employed, the first element of the differential 45, whilst the third element of the differential is driven in the same direction as the first element through any suitable gearing, as shown chain drive 46, by the flanged metal wheels 2, the third element however being driven at half the speed of the first element. The second element of the differential is connected through suitable mechanism to a compressor 51 which, on slip occurring, is driven by the second element of the differential to build up pressure which may be transmitted by any of the previously described methods to increase load on the axle. The driving wheels 5 are mounted on the auxiliary axle 6 which carries a crown wheel 6' in mesh with a bevel 15' mounted on the transmission shaft 15. When slip has ceased by pressure being built up, the pressure can conveniently be released e. g. by a suitable leak or by a natural leak past the piston.

In the arrangement shown in Figure 19A the differential device 45, and pump 51 are adapted to be operated should slip occur between either of the wheels 5 on the auxiliary axle 6 and the metal wheels 2 mounted on the axle 2'. In order that this may be effected the first element of the differential 45 is driven by the transmission shaft 15 through reduction gearing 150, the driving wheels 5 being mounted on an auxiliary axle 6 of the automobile type so that if either of the wheels 5 slip, the transmission shaft speeds up to operate through the differential device the pump 51 whereby the loading on the auxiliary axle is adjusted to the desired amount. It is obvious that the first element of the differential may be actuated from the gear box instead of from the transmission shaft and that the third element of the differential may be driven by an additional axle having flanged wheels. The arrangement shown in Figure 19B is such that the pump 51 is actuated through the differential 45 should slip occur between either of the wheels

5 and the rails. In this arrangement the first member of the differential is driven by one of the wheels 5 whilst the second member is driven by the other wheel 5 through a crossed belt or chain, the pump 51 being driven by the third member.

Alternatively to the arrangement shown in Figures 19 and 20, that shown in Figure 21 may be employed in which the auxiliary wheels 5 actuate a pump 52 whilst the flanged wheels 2 drive a second pump 53. The exhaust from the pump 52 is connected to the inlet of the pump 53, the exhaust of which is connected to the inlet of the pump 52. Between the exhaust of the pump 52 and the inlet of the pump 53 is arranged a chamber 54 in which is provided a diaphragm 55 carrying a valve 56 adapted to open or close the supply of fluid under pressure from any convenient source to a cylinder 57 fast with the auxiliary frame 4, in which cylinder is arranged a piston 58 fast with the frame 1. 54' is a gauge showing the pressure acting upon the diaphragm 55, and 54'' is a second gauge, located between the chamber 54 and the cylinder 57. 59 is a compensating tank from which, when liquids are used, the pump 52 can draw liquid. When there is no slip between the auxiliary axle 6 and the rail 8 the pumps 52, 53 provide a closed circuit for the liquid no pressure being produced, whilst when slip occurs the pump 52 accelerates, thereby increasing the load on the auxiliary axle 6. This building up of pressure continues so long as the slip persists, the pressure being released when slip has ceased through a convenient leak 60. If desired a differential pump or compressor may be employed in place of the two pumps 52, 53, one member of the pump being driven by the auxiliary axle 6 and the other by the flanged wheel 2. In order that the vehicle may be driven in reverse the compensating tank 59, is connected both to inlet and exhaust of the pump 52, suitable nonreturns 59' being provided.

A further modification is illustrated in Figures 22 and 23 for automatically increasing the load on the wheels 5 when slip occurs. In these figures there is provided a differential relay device one member 61 of which is actuated by the auxiliary axle 6 and the other 62 by the vehicle axle 2' in such a way that the middle or driving member 63 of the differential relay device, which receives the differential motion remains stationary when no slip occurs. The members 61 and 62 of the differential relay device drive drums 64, 65 respectively, which drums rotate within a third drum 66 carrying the third member 63 of the relay the drums 64, 65, 66 being contained within a casing 67 containing oil.

The third member 63 of the relay is adapted to make contact with one or other of two contacts 68 of an electric circuit which includes a solenoid 69, battery 70 and armature 71. The solenoid 69 is contained within a casing 72 through which fluid pressure from any convenient source may be supplied via a pipe 73 to a cylinder 74 in which is adapted to reciprocate a piston 75. The armature 71 is so shaped that on actuation of the solenoid it can open or close the entrance to the pipe 73. When no slip occurs, fluid pressure is supplied to the cylinder 74 through a pipe 76 communicating with a chamber 77 closed by a diaphragm 78 carrying a valve 79. The chamber 75

11 is also provided with a pipe 80 which communicates with the pipe 73 the valve 81 being positioned at the point of juncture of the pipes 80 and 73. It will be noticed that pressure can be supplied to the cylinder 74 through the pipe 76, chamber 77 and pipe 80 but if this pressure exceeds that required the diaphragm 78 is operated to move the valve 79 onto its seat, thereby cutting off further supply of pressure. When slip occurs the drum 66 is caused to oscillate owing to the friction of the oil and closes the electric circuit, by making contact between the member 63 and either of the contacts 68. The solenoid 69 is thereby energized and the diaphragm 71 pulled back against the action of a spring 82 thereby opening the entrance to the pipe 73 so that pressure on the piston 75 is increased through the pipe 73 at the same time closing the valve 81 at the point of juncture of the pipes 73 and 80. 20 83 represents a leak for relieving the pressure when slip has ceased to occur, whilst the increased pressure may automatically unload when the vehicle is over-running the driving axle.

The differential operating devices are preferably so arranged that when no slip occurs, there will be a slow unloading action which will automatically unload the auxiliary axle to a fixed but preferably adjustable predetermined minimum value. Means may also be provided for limiting the loading to a fixed but preferably adjustable predetermined maximum value.

It will be seen that with any such arrangements, on starting the vehicle or when the vehicle is on steep gradients under adverse conditions, as regards the coefficient of friction between the auxiliary driving wheels and rails, the wheels will first slip but this action will automatically cause an increase in the loading on such wheels until the slip will cease or will be reduced to very small proportions. As soon as slip has ceased the drive will become normal and the load will either be gradually diminished as for example on account of the fixed or adjustable leakages when fluids are used, or by the positive gradual unloading action which will occur when the differential control system is so arranged that when no slip occurs there shall actually be a slow unloading action either up to a minimum load determined beforehand or up to a load at which slip will occur again.

This control of loading is automatically responsive to changes in the relative rates of rotation of the first-named wheels and the wheels on said auxiliary axle so that the driver of the vehicle need pay no attention to what load is actually on the auxiliary axle nor need he take into account the load on the vehicle which load will of course vary with the number of passengers or goods carried.

The invention therefore ensures the minimum loading necessary for providing the grip to ensure propulsion of the vehicle, thus during the greater part of the driving time the load on the auxiliary axle will be considerably reduced as compared with an arrangement in which fixed loading is provided; this will result in low tire wear and higher overall efficiency, as if a fixed loading is provided, this must of necessity correspond to the maximum loading necessary to secure grip under the most adverse conditions, as for the condition when the friction between rail and rubber tire drops temporarily to a very low value. The invention enables the use of sand for assisting wheel grip to be dispensed with except

in very exceptional cases such as starting on ice or grease covered rails.

If the vehicle is arranged to run in both directions, means can be provided to cause operation of the loading devices no matter in which direction the wheels rotate; in the case when fluid pressure is relied upon to vary the loading, means could be provided to reverse the fluid connections; when relays are employed this can be effected very simply, the relays actuating the loading devices in the same direction no matter in which direction the driving wheels are rotating; for an entirely mechanical action, through differential control gear and mechanical loading gear, this could be effected either by suitable reversing clutches or by a linkage of the toggle type which will act in the same direction irrespective of the direction of actuation of the differential control gear.

Referring to Figure 24, the tire shown herein is 20 of the well known pneumatic type whilst that shown in Figure 25 is of the solid rubber type.

The recesses in the tire shown in Figure 25 may, if desired, be arranged diagonally say at an angle between 30° and 45° across the tread surface. Such recesses are necessary when ordinary rubber is used to allow water trapped between the tire and the rail to be expelled. In place of employing rubber as the tread surfaces of the tires carried by the auxiliary axle, any surface 30 having a high coefficient of friction may be employed such for example as bonded fibrous fabrics such as cotton asbestos, with or without rubber reinforcement, or alternatively, tires of metal of a high coefficient of friction elastically supported 35 e. g. on rubber or spring cushions, in which case the metal tire could be flanged.

Figure 26 represents diagrammatically a complete railway vehicle constructed in accordance with this invention.

What I claim is:

1. A railway vehicle in which in addition to the usual flanged metal wheels there is provided an auxiliary axle suspended from the vehicle, wheels on said auxiliary axle which wheels constitute 45 driving wheels, and means responsive to changes in the relative rates of rotation of the first-named wheels and the wheels on said auxiliary axle for automatically adjusting the loading on said auxiliary axle when slip occurs between any 50 wheel on the auxiliary axle and a rail whereby the wheels on said auxiliary axle can be pressed into contact with the rails to such a degree as will enable them to drive the vehicle to suit varying 55 conditions, the flanged metal wheels retaining their guiding and supporting function.

2. A railway vehicle in which in addition to the usual flanged metal wheels there is provided an auxiliary axle, an underframe articulated to the vehicle at least one point, said auxiliary axle being suspended from said underframe, wheels on said auxiliary axle which wheels constitute driving wheels, and means responsive to changes in the relative rates of rotation of the first-named 65 wheels and the wheels on said auxiliary axle for automatically adjusting the loading on said auxiliary axle when slip occurs between any wheel on the auxiliary axle and a rail whereby the wheels on said auxiliary axle can be pressed into contact 70 with the rails to such a degree as will enable them to drive the vehicle to suit varying conditions, the flanged metal wheels retaining their guiding and supporting function.

3. A railway vehicle in which in addition to the 75

axle and to said means for varying the pressure on the auxiliary axle in such a manner that when slip occurs between the wheels on said auxiliary axle and the rails the pressure on said auxiliary axle is automatically increased so long as slip occurs whereby the wheels on said auxiliary axle can be pressed into contact with the rails to such a degree as will enable them to drive the vehicle to suit varying conditions, the flanged metal wheels retaining their guiding and supporting function.

12. A railway vehicle in which in addition to the usual flanged metal wheels there is provided an auxiliary axle suspended from the vehicle, 15 wheels on said auxiliary axle which wheels constitute driving wheels, means for varying the pressure on the auxiliary axle, a differential device connected to the wheels on said auxiliary axle and to said means for varying the pressure 20 on the auxiliary axle in such a manner that when slip occurs between the wheels on said auxiliary axle and the rails the pressure on said auxiliary axle is automatically increased so long as slip occurs, whereby the wheels on said auxiliary axle can be pressed into contact with the rails to such a degree as will enable them to 25 drive the vehicle to suit varying conditions, the flanged metal wheels retaining their guiding and supporting function, and means whereby the 30 wheels on said auxiliary axle can be raised out of engagement with the rails and pressed into contact with the flanged wheels in order to drive the vehicle in reverse direction.

35 13. A railway vehicle in which in addition to the usual flanged metal wheels there is provided an auxiliary axle suspended from the vehicle, wheels on said auxiliary axle which wheels constitute driving wheels, and means responsive to changes in the relative rates of rotation of the 40 first-named wheels and the wheels on said auxiliary axle including a relay device connected to said auxiliary axle and to an axle of the vehicle in such a manner that when slip occurs between the wheels on the auxiliary axle and the rails 45 the pressure on the auxiliary axle is automatically increased so long as slip occurs, whereby the wheels on said auxiliary axle can be pressed into contact with the rails to such a degree as will enable them to drive the vehicle to suit varying 50 conditions, the flanged metal wheels retaining their guiding and supporting function.

14. A railway vehicle in which in addition to the usual flanged metal wheels there is provided an auxiliary axle suspended from the vehicle, wheels on said auxiliary axle which wheels constitute driving wheels, means responsive to changes in the relative rates of rotation of the first-named wheels and the wheels on said auxiliary axle including a relay device connected to 55 said auxiliary axle and to an axle of the vehicle in such a manner that when slip occurs between the wheels on the auxiliary axle and the rails the pressure on the auxiliary axle is automatically increased so long as slip occurs, whereby the 60 wheels on said auxiliary axle can be pressed into contact with the rails to such a degree as will enable them to drive the vehicle to suit varying conditions the flanged metal wheels retaining their guiding and supporting function, and means 65 whereby the wheels on said auxiliary axle can be raised out of engagement with the rails and pressed into contact with the flanged wheels in 70 order to drive the vehicle in reverse direction.

75 15. A railway vehicle in which in addition to the usual flanged metal wheels there is provided an

auxiliary axle suspended from the vehicle, wheels on said auxiliary axle which wheels constitute driving wheels, fluid pressure means for varying the pressure on the auxiliary axle, and a differential device connected to the wheels on said auxiliary axle and to said fluid pressure means for varying the pressure on the auxiliary axle in such manner that when slip occurs between the wheels on said auxiliary axle and the rails the pressure on said auxiliary axle is automatically increased so long as slip occurs whereby the wheels on said auxiliary axle can be pressed into contact with the rails to such a degree as will enable them to drive the vehicle to suit varying conditions the flanged metal wheels retaining their guiding and supporting function.

16. A railway vehicle in which in addition to the usual flanged metal wheels there is provided an auxiliary axle suspended from the vehicle, wheels on said auxiliary axle which wheels constitute driving wheels, means responsive to changes in the relative rates of rotation of the first-named wheels and the wheels on said auxiliary axle including a fluid pressure relay device connected to said auxiliary axle and to an axle of the vehicle in such a manner that when slip occurs between the wheels on the auxiliary axle and the rails the pressure on the auxiliary axle is automatically increased so long as slip occurs whereby the wheels on said auxiliary axle can be pressed into contact with the rails to such a degree as will enable them to drive the vehicle to suit varying conditions the flanged metal wheels retaining their guiding and supporting function, and means whereby the wheels on said auxiliary axle can be raised out of engagement with the rails and pressed into contact with the flanged wheels in order to drive the vehicle in reverse direction.

17. A railway vehicle in which in addition to 40
the usual flanged metal wheels there is provided
an auxiliary axle suspended from the vehicle,
wheels on said auxiliary axle which wheels con-
stitute driving wheels, and means responsive to
changes in the relative rates of rotation of the 45
first-named wheels and the wheels on said auxil-
iary axle including a fluid pressure relay device
connected to said auxiliary axle and to an axle
of the vehicle in such a manner that when slip
occurs between the wheels on the auxiliary axle 50
and the rails the pressure on the auxiliary axle
is automatically increased so long as slip occurs
whereby the wheels on said auxiliary axle can
be pressed into contact with the rails to such a
degree as will enable them to drive the vehicle to 55
suit varying conditions the flanged metal wheels
retaining their guiding and supporting function.

18. A railway vehicle in which in addition to the usual flanged metal wheels there is provided an auxiliary axle suspended from the vehicle, 60 wheels on said auxiliary axle which wheels constitute driving wheels, means for varying the pressure on the auxiliary axle, and means responsive to changes in the relative rates of rotation of the first-named wheels and the wheels 65 on said auxiliary axle including a relay device connected to the wheels on said auxiliary axle and to said means for varying the pressure on the auxiliary axle in such a manner that when slip occurs between the wheels on said auxiliary axle 70 and the rails pressure on said auxiliary axle is automatically increased so long as slip occurs whereby the wheels on said auxiliary axle can be pressed into contact with the rails to such a degree as will enable them to drive the vehicle to 75

suit varying conditions, the flanged metal wheels retaining their guiding and supporting function.

19. A railway vehicle in which in addition to the usual flanged metal wheels there is provided
5 an auxiliary axle suspended from the vehicle, wheels on said auxiliary axle, which wheels constitute driving wheels, tires on said wheels said tires being of resilient material and having a substantially flat tread such as are used on heavy
10 road vehicles, an adjustable axle mount for said auxiliary axle whereby the latter can be moved

in a direction transverse to the axis of the vehicle to enable different parts of the tread of the tires of the wheels on said auxiliary axle to engage the rails, and means for adjusting the loading on said auxiliary axle whereby the wheels on said auxiliary axle can be pressed into contact with the rails to such a degree as will enable them to drive the vehicle to suit varying conditions, the flanged metal wheels retaining their guiding and supporting function.

GEORGE CONSTANTINESCO.
